CLAIM

The ornamental design for a dock stabilizer as shown and described.

DESCRIPTION

FIG. 1 is a top perspective view of a dock stabilizer showing the new design;
FIG. 2 is a front elevation of the dock stabilizer;
FIG. 3 is a rear elevation of the dock stabilizer;
FIG. 4 is a top plan view of the dock stabilizer; and
FIG. 5 is a bottom plan view of the dock stabilizer.
FIG. 6 is a right side elevation of the dock stabilizer; and,
FIG. 7 is a left side elevation of the dock stabilizer.

1 Claim, 7 Drawing Sheets
